ELECTRIC FOOD WARMER BABY DISH

Ruth G. Ehrlich, 80—26 249th St.,
Bellerose, N.Y. 11426

Filed Feb. 14, 1972, Ser. No. 226,362

Term of patent 7 years

Int. Cl. D7—01

U.S. Cl. D7—69

FIG. 1

3—

FIG. 2

4—

FIG. 3

FIG. 4

FIG. 1 is a top plan view of an electric food warmer baby dish showing my new design;

FIG. 2 is a bottom plan view thereof;

FIG. 3 is a side elevation thereof taken along lines 3—3 of FIG. 1; and

FIG. 4 is a side elevation thereof taken along lines 4—4 of FIG. 2.

I claim:

The ornamental design for an electric food warmer baby dish, substantially as shown.
